UNITED STATES PATENT OFFICE

EDWIN C. LARRY, OF ROCHESTER, NEW YORK, ASSIGNOR TO GENERAL RAILWAY SIGNAL COMPANY, OF ROCHESTER, NEW YORK

INTERLOCKING SYSTEM FOR RAILROADS

Application filed July 7, 1930. Serial No. 465,863.

This invention relates to a switch machine control apparatus for railway systems and more particularly to a switch machine control apparatus of the dynamic indication type.

In an interlocking system of the interlocked lever type, it has been found necessary to prevent the stroke of the lever being completed until the function controlled by such lever has responded to initial movement of such lever, and further it has been found expedient to lock the lever in an extreme position for detector locking purposes. In accordance with the present invention it is proposed to employ dynamic indication current generated by the function apparatus, such as the switch machine, for unlocking the lever and permitting movement of the lever from the half to the full position, that is, from the half normal to the normal position or from the half reverse to the full reverse position, and in accordance with the present invention it is proposed to employ the same locking means for detector locking as is used for indication locking. It is further proposed, in accordance with the present invention, to use the dynamic indication current generated by the motor of the switch machine, for example, for the purpose of picking up a stick relay and then holding the stick relay energized so long as the lever remains in the then operated half normal or half reverse position, as the case may be. It is further proposed to provide means for effecting deenergization of this stick relay in the event the lever is moved through its intermediate position, this in order to prevent the operator from very quickly moving his lever from, say, the half normal to the full reverse position, or from the half reverse to the full normal position, for if this were possible the operator might take advantage of an indication received from a switch machine due to completion of its normal stroke for releasing his lever for movement to the full reverse position.

Other objects, purposes and characteristic features of the invention will in part be pointed out hereinafter and in part be obvious from the accompanying drawing.

In describing the invention in detail reference will be made to the single drawing, which shows the invention applied to a switch machine located at a distant point with reference to the control lever.

55

Structure

Referring to the drawing the track rails on the main track have been shown divided into an approach section A and a detector track section D, by insulating joints 2, a track switch S being shown for diverting traffic into the siding containing the track rails 3. This track switch S is preferably operated by the switch machine SM, including a motor M and a reversing switch having movable contacts 5 and 6, which contacts are operated upon completion of the operating stroke of the switch machine.

60

65

This switch machine SM is controlled by a lever L in the interlocking plant, which lever may be interlocked with the levers of conflicting routes mechanically or may be correspondingly interlocked electrically by suitable means well known in the interlocking art, and as conventionally shown by the lever of a conflicting route having contacts 33-34 included in the detector locking circuit. This lever L includes movable contacts 10, 11, 12, 13 and 14, the functions of which will be pointed out hereinafter. The lever L is also provided with locking shoulders 15 and 16, over the top of which shoulders are located force drop cams FD for forcing the locking plunger LP to its lower locked position when the lever L is moved to the full normal, the full reverse or to the intermediate position, respectively. This locking plunger LP is urged to its lower position by gravity and may be raised from its lower locked position by the indication magnet IM, this indication magnet IM being controlled through the medium of an indication relay IR, in a manner as more fully described hereinafter. In order to avoid the substantially continuous flow of current through the indication magnet IM there have been provided normally open energy saving contacts ES, which contacts may be closed by the operator upon gripping the

70

handle of the lever L and depressing the push button PB.

Referring to the circuit diagram, attention is directed to the fact that the switch machine SM and the upper winding of the indication relay IR are controlled through a series circuit by energy received from one battery B¹, whereas the lower winding of this stick relay IR and the indication and detector locking circuits receive their current from another battery B², this precaution being taken to avoid against unauthorized crosses, but if desired one of these batteries may be eliminated. It should be noted that the normal, half normal, reverse, half reverse and middle positions of the lever have been designated N, HN, R, HR and I, respectively. Having now described the various elements of the system, it is believed expedient to consider the operation of the system, this in order to more clearly understand its operating characteristics and certain advantages afforded by the novel system under consideration.

Operation

The switch machine SM has been shown in its normal main track position, and the lever L has been shown in its normal pushed-in position. Let us assume that the operator wishes to move the track switch S to the take-siding position through the medium of the switch machine SM. In order to do this he will depress the push button PB, and in the event that the detector track circuit is unoccupied, as manifested by the track relay DT shown conventionally by a dotted line, and the track section A is unoccupied, as manifested through the medium of the track relay TA, the following circuit for the indication magnet IM is completed:—beginning at the terminal of the battery B², wire 17, contacts 33—34 of the conflicting lever L¹, wire 18, front contact 19 of the track relay DT, wire 20, front contact 21 of the track relay TA, wire 22, contacts 13—23, wires 24 and 25, energy-saving contacts ES, wire 26, back contact 27 of the stick relay IR, wire 28, coil of the indication magnet IM, wires 29, 30 and 31, and back to the battery B². The flow of current in the circuit just traced will lift the movable core 32 of the indication magnet IM, thereby raising the locking plunger LP to a position to free the locking shoulder 15, permitting movement of the lever L from its normal position N, upon which the contacts 13—23 open, and effect deenergization of the indication magnet IM.

The lever L may, however, be moved to the half reversed position HR even though the combined indication and lock magnet IM is now deenergized, thereby closing the reverse circuit for the switch machine SM, which may be traced as follows:—beginning at the positive terminal of the battery B¹, wire 35, contact 11—36, wires 37 and R, contact 5 of the

switch machine SM, wire 38, armature 39 of the motor M, wire 40, contact 6, wires 41 and 42, field winding 43 of the motor M, and to common return wire C, connected to the negative terminal of the battery B¹. The closure of this circuit operates the switch machine SM, and in turn the track switch S, to its reverse take-siding position, and when the stroke of the switch machine has been completed, the contacts 5 and 6 will be operated by snap action to the dotted position. In this, the dotted position of the contacts 5 and 6 of the switch machine SM, and with the motor M rotating by its inertia in a direction to move the track switch still further toward the take-siding position, dynamic current is generated in this series motor M, which dynamic current may flow through the upper winding of the indication relay IR through the following circuit:—beginning at the armature 39, wires 40 and 46, contact 5, wires N and 47, contacts 10—48, wire 49, upper winding of the indication relay IR, wires 50 and C, field winding 43 of the motor M, wires 42 and 51, contact 6 of the switch machines M, wires 52 and 38, and back to the armature 39. The flow of this dynamic current effects energization of the indication relay IR, and with its contact 55 once picked up this relay IR is stuck up through the following stick circuit:—beginning at the positive terminal of the battery B², wires 56 and 57, contacts 12—58, wires 59 and 60, stick contact 55 of the relay IR, wires 61, lower winding of the indicating relay IR, wires 62, 30 and 31, and back to the battery B².

With the indicating relay IR now energized in response to the flow of dynamic indication current and maintained up through its stick circuit, the indicating magnet IM is energized through the following circuit:—beginning at the positive terminal of the battery B², wires 56 and 57, contacts 12—58, wires 59 and 67, front contact 27 of the indicating relay IR, wire 28, winding of the indication magnet IM, wires 29, 30 and 31, and back to the battery B². Flow of current in the circuit just traced effects lifting of the lock pawl LP, thereby permitting movement of the lever L from its half reverse to its full reverse position, in which latter position the lever L will permit all non-conflicting levers for the present position of the lever L of the interlocking plant to be operated. Also, the operator need not move this lever immediately, for with the indication relay IR energized by a stick circuit it will remain in its energized position irrespective of the flow of dynamic indication current.

It may be pointed out here, that had the operator when his lever assumed the half reverse position HR, and with the indication relay IR energized, suddenly changed his mind and decided to move the lever L back to the full normal position, such movement

would have closed the intermediate contact 14-70, and thereby would have completed an energizing circuit for the pull-down magnet 71 of the indicating relay IR through the following circuit:—beginning at the positive terminal of the battery B², wire 73, winding of the pull-down magnet 71, wire 74, contacts 14-70, wires 75 and 31, and back to the negative terminal of the battery B². Even though the lever L is moved very quickly toward this improper normal position, the pull-down coil 71 will pull down the contacts 27 and 55 very quickly, and force drop cam FD will force the lock plunger LP down between the shoulders 15 and 16. The pull-down coil 71 of the indication relay IR is designed to pull down the contacts 27 and 55 of this indication relay IR irrespective of the flow of conflicting currents in the two windings of the indicating relay IR, even though such conflicting current is not likely to flow, so that these contacts 55 and 27 will be very quickly moved to their retracted position, thereby breaking the circuit for the indicating magnet IM and preventing movement of the lever L beyond the intermediate position. Not only this, but the operator will be penalized for having mis-operated his lever L, now that he has entirely lost the indication which was manifested by the picking up of the indicating relay IR, so that the switch machine must be operated specially to obtain the desired indication. For instance, with switch machine now assuming the reverse position the operator must first operate it to the normal position, and he must thereafter operate it to the reverse position to obtain dynamic indication current with the lever in the half reverse position, so that he can, upon unlocking of the lever L, move it to the full reverse position without moving it through the intermediate or middle position.

In view of the symmetrical arrangement of the circuits and contact, it is obvious that movement of the lever L to the half normal position will effect operation of the switch machine SM back to the normal position through the medium of the normal wire N, and similarly when the switch machine SM has been operated to such normal position, dynamic indication current will be caused to flow through the upper winding of the indication relay IR for reasons heretofore given, this dynamic indication circuit being readily traced in view of the fact that it is symmetrical to the dynamic indication circuit heretofore traced.

Although a simple conventional switch machine SM has been illustrated it is desired to be understood that a switch machine having many other features, such as reversibility in mid-stroke, as for instance shown in the patent to Howe No. 1,466,903, dated September 4, 1923, and having other desirable characteristics, may be employed. Also, in-

stead of employing electric interlocking between levers, having contacts of all conflicting levers included in series with one of the wires 18, 20 or 22, as shown by the contacts 33-34, the conflicting levers may be locked mechanically by suitable lock bars and lock dogs. In other words, well known mechanical interlocking between levers may be used instead of the electro-mechanical interlocking shown, if desired.

It is also to be understood that although no cross-protection relay or other suitable protection apparatus has been shown, such apparatus may be employed in the present system, if desired. Also such apparatus as time release devices, and other auxiliary apparatus, may be added to the present system without departing from the present invention.

Having thus shown and described one rather specific embodiment of the present invention, and having illustrated many of the elements of the system conventionally, it is desired to be understood that this is done for the purpose of simplifying the description of a system embodying the invention, and that the particular arrangement illustrated has not been selected for the purpose of showing the scope of the invention or the exact construction employed in practicing the same, and that various changes, modifications and additions may be made to adapt the invention to the particular problem encountered in practicing the same all without departing from the spirit or scope of the invention except as demanded by the scope of the following claims.

What I claim as new is:—

1. In combination; a switch machine for operating railway track switches; a lever having a half normal position and a half reverse position for operating said switch machine; and locking means for preventing said lever being moved to the full normal position unless said switch machine has been operated to the normal position and preventing said lever being moved to the full reverse position unless said switch machine has been first operated to the reverse position comprising; a stick relay having a pick-up and a stick circuit, said pick-up circuit including the armature of the operating motor of said switch machine when said switch machine is being dynamically braked, and said stick circuit including a contact of said lever closed when said lever applies operating current to said switch machine to operate it to the last operated position, and means controlled by said stick relay for permitting said lever to be moved to the corresponding full position.

2. In combination; a switch machine for operating railway track switches; a lever having a full normal position a half normal position, a full reverse position and a half

- reverse position for operating said switch machine; and locking means for preventing said lever being moved to the full normal position unless said switch machine has been operated to the normal position and preventing said lever being moved to the full reverse position unless said switch machine has been first operated to the reverse position comprising; a stick relay having a pick-up and a stick circuit, said pick-up circuit including the armature of the operating motor of said switch machine when said switch machine is being dynamically braked, and said stick circuit including a contact of said lever closed when said lever assumes the corresponding half position, and means controlled by said stick relay for permitting said lever to be moved to the corresponding full position.
- 20 3. In combination; a switch machine for operating railway track switches; a lever having a full normal position, a half normal position, a full reverse position and a half reverse position for operating said switch machine; and locking means for preventing said lever being moved to the normal position unless said switch machine has been operated to the normal position and preventing said lever being moved to the reverse position unless said switch machine has been first operated to the reverse position comprising; a stick relay, a pick-up circuit for said stick relay including the motor of said switch machine when the switch machine has completed its stroke and including a contact on said lever closed when assuming the corresponding half position, a stick circuit for said relay including a contact closed when said lever assumes said corresponding half position, and release means controlled by said stick relay for permitting said lever to be moved to the corresponding full position.
- 45 4. In combination; a switch machine for operating railway track switches; a lever having a full normal position, a half normal position, a full reverse position and a half reverse position for operating said switch machine; and locking means for preventing said lever being moved to the full normal position unless said switch machine has been operated to the normal position and preventing said lever being moved to the full reverse position unless said switch machine has been first operated to the reverse position comprising; a stick relay, a pull-down coil for said relay for pulling down the contacts of said relay upon energization of said coil, a pick-up circuit for said relay including the motor of said switch machine when said switch machine has completed its stroke and including a contact on said lever closed when assuming the corresponding half position, a stick circuit for said relay including a contact closed when said lever assumes said corresponding

half position, a circuit for said pull-down coil closed when said lever assumes the middle position, and release means controlled by said stick relay for permitting said lever to be moved to the corresponding full position. 70

5. In combination; a switch machine for operating railway track switches; a lever having a normal position and a reverse position for operating said switch machine; and locking means for preventing said lever being moved to the normal position unless said switch machine has been operated to the normal position and preventing said lever being moved to the reverse position unless said switch machine has been first operated to the reverse position comprising; a stick relay having a pick-up and a stick circuit, said pick-up circuit including the armature of the operating motor of said switch machine when said switch machine is being dynamically braked, and said stick circuit including a contact of said lever closed when said lever applies operating current to said switch machine to operate it to the last operated position, release contacts which if closed manifest that it is safe to operate said switch, and means effective when said stick relay is energized to unlock said lever irrespective of the condition of said release contacts and effective to unlock said lever if said stick relay is deenergized only in the event said release contacts are closed. 80

6. In a system of the class described; a distant switch machine having a normal circuit and a reverse circuit; a local lever for controlling said switch machine having a full normal position and a full reverse position, contacts on said lever for completing said normal circuit and for completing said reverse circuit, a stick relay having a pick-up circuit energized by dynamic indication current generated by the inertia of the motor of said switch machine after said switch machine has completed its operating stroke, and a front contact on said stick relay which if closed permits other traffic controlling apparatus to be operated which was locked against operation prior to such operation of said switch machine. 100

7. In a system of the type described, in combination, a lever, locking means for locking said lever against movement toward and away from its two extreme full normal and full reverse position, force drop means for forcing said locking means into each of its locking positions upon movement of said lever to such positions, a switch machine controlled by said lever, a stick relay picked up by dynamic current generated by the motor of said switch machine when said switch machine has completed its stroke, and means for releasing said locking means effective if said stick relay is energized. 115

8. In a system of the type described, in combination, a lever, locking means for lock-

ing said lever against movement toward and away from its two extreme full normal and full reverse position, force drop means for forcing said locking means into each of its locking positions upon movement of said lever to such positions, a switch machine controlled by said lever, a stick relay picked up by dynamic current generated by the motor of said switch machine when said switch machine has completed its stroke, an approach section leading to the track switch operated by said switch machine, and means for releasing said locking means effective if said stick relay is energized and also effective if said stick relay is deenergized and said approach section is unoccupied.

9. In a system of the type described, in combination, a lever having two intermediate and two extreme positions, locking means for locking said lever against movement from a normal intermediate position to its normal extreme position, a switch machine controlled by said lever, a stick relay picked up by dynamic current generated by the motor of said switch machine when said switch machine has completed its stroke and with said lever assuming an intermediate position, and means for releasing said locking means effective only if said stick relay is energized.

30 10. In a system of the type described, in combination, a lever, locking means for locking said lever against movement toward and away from its two extreme full normal and full reverse positions, a switch machine controlled by said lever, a stick relay picked up by dynamic current generated by the motor of said switch machine when said switch machine has completed its stroke, and means for releasing said locking means for movement of said lever toward an extreme position effective if said stick relay is energized and effective to release said locking means for movement of said lever away from an extreme position when said stick relay is deenergized and traffic conditions are safe.

45 11. In a system of the type described, in combination, a lever, locking means for locking said lever against movement from an intermediate toward an extreme position, a switch machine controlled by said lever, a stick relay picked up by dynamic current generated by the motor of said switch machine when said switch machine has completed its stroke and with said lever assuming an intermediate position, means for releasing said locking means effective if said stick relay is energized, and means effective when said lever assumes the middle position for effecting deenergization of said stick relay.

50 12. In a system of the type described, in combination, a lever, locking means for locking said lever against movement toward and away from its two extreme full normal and full reverse positions, a switch machine con-

trolled by said lever, a stick relay picked up by dynamic current generated by the motor of said switch machine when said switch machine has completed its stroke, means for releasing said locking means for movement of said lever toward an extreme position effective if said stick relay is energized and effective to release said locking means for movement of said lever away from an extreme position when said stick relay is deenergized and traffic conditions are safe, and means effective when said lever assumes the middle position for effecting deenergization of said stick relay.

55 In testimony whereof I affix my signature. EDWIN C. LARRY.
